UNITED STATES PATENT OFFICE.

JOHN McCAHEY AND GEORGE F. McCAHEY, OF PROVIDENCE, RHODE ISLAND, ASSIGNORS, BY DIRECT AND MESNE ASSIGNMENTS, TO THE DEMING BRAIDING COMPANY, A CORPORATION OF RHODE ISLAND.

CARRIER FOR BRAIDING-MACHINES.

SPECIFICATION forming part of Letters Patent No. 790,649, dated May 23, 1905.

Application filed June 23, 1904. Serial No. 213,788.

To all whom it may concern:

Be it known that we, JOHN McCAHEY and GEORGE F. McCAHEY, residents of the city of Providence, in the county of Providence and State of Rhode Island, have invented certain new and useful Improvements in Carriers for Braiding-Machines; and we do hereby declare that the following is a full, clear, and exact description thereof, reference being had to the accompanying drawings, and to the figures of reference marked thereon, which form a part of this specification.

This invention relates to spool-carriers for braiders and the like, and has for its object to produce a simple and practical carrier that has many structural advantages over the ordinary carrier used for this purpose.

A further object of the invention is to greatly increase the speed at which the carrier may safely be run, first, by reducing the liability of overrunning of the yarn-spool by the use of more reliable mechanism herein-after described, and, second, by reducing the height of the carrier, which at once reduces its top-heaviness and a consequent liability of cramping in the raceways by the action of the centrifugal force upon it. These improvements are fully set forth in the following specification, particularly pointed out in the appended claims, and illustrated in the accompanying drawings.

Figure 1 shows a side elevation of the spool-carrier threaded up and in position to be used. Fig. 2 is a central sectional elevation showing the tubular standard with the spring therein for assisting the bottom weight to apply tension to the yarn. Fig. 3 is a rear elevation of the carrier. Fig. 4 is a section on line of Fig. 1, showing a tubular standard with a flat back, on which latter the bottom weight slides. Fig. 5 is a perspective view of the latch and guide-wire, showing the flat spring attached thereto. Fig. 6 is a plan view of the latch, showing it in engagement with the spindle, the notched portion of said spindle being in section.

In the drawings at 1 is the foot of the car-

rier, on the rear of which is preferably cast a tubular standard 2. The back of this standard is slotted at 20 and is made comparatively flat for a portion of its length, with projecting edges at 33 on each side thereof. The bottom weight 4 is loosely held to engage these projecting edges 33, so it may slide freely up and down on the said back. The upper end of this flat portion is cut away to allow the said weight to be readily removed therefrom. Into the upper end of this tube is screwed a plug 5, through which is drilled a small hole 6.

The spindle 9 is pointed or rounded off at its upper end, so that the latch may be pressed over it more easily. Said spindle is also notched out at 10 to receive the forked end of said latch. Riveted to this latch at 12 is the flatspring 11. (See Figs. 5 and 6.) This spring is held down in position on the fork by the lug 13, that extends out over it. When the forked end of the latch is pressed down over the pointed end of the spindle 9, this spring 11 is compressed and draws the arm 14 of said fork over into the notched portion 10 of the spindle 9, as shown in Fig. 6. This notch effectually prevents the latch from being raised too high and also prevents it from being thrown off of the carrier when running at a high velocity. Depending from one end of this latch is the guide-pin 7. The pin extends down through the hole 6 in the plug 5 into the tubular portion of the standard 2. On the back of the bottom weight 4 is a lug 16, in which the eye 17 is made for the reception of the thread 18 when the carrier is threaded up. One end of the pin 19 is fixed in this lug 16 and extends through the slot 20 into the hollow standard 2. Resting on this pin within the hollow standard is the loosely-fitting guiding-plug 21, against which the lower end of the tension-spring 22 rests.

The operation of this invention is further described as follows: The spool 23, on the upper end of which are formed ratchet-teeth 24, is placed on the spindle 9 on the carrier. The latch 8 is then swung around over the spindle 9 and pressed down over its pointed end. The

flat spring 11 engages the rounded side of the spindle, drawing the arm 14 under the notch, and prevents the latch from being disengaged therefrom, but allows it to move freely up and down on the spindle. By this improved construction there are no loose parts liable to be thrown off by the high velocity of the running carrier to fall among the mechanism. Another object in this construction and method 10 of operating the latch is that the carrier is kept down to minimum height, thus reducing its top-heaviness and liability to cramp in the raceways.

The threading of this carrier is very simple 15 and may be done after the spool is in place on the spindle, the thread being first passed through the eye 25 in the outwardly-projecting lug 26, then down through eye 17 in the bottom weight, and thence by a straight lead 20 up through the eye 27 in the lug 28. By inclosing the spring in the tubular standard it is out of the way and cannot become entangled with the yarn.

It is customary in the old-style carriers to 25 make the bottom weight heavy enough to regulate the tension on the yarn and compensate for the ever-changing length of the same as the carrier passes in and out in braiding; but in this improved device the bottom weight is 30 made very light, and a spring 22 is employed to supply the necessary tension. This spring is found in practice to work much better than the heavy weight, as it acts to return the guide or weight 4 very quickly. A heavy weight 35 when thrown upward by a sudden impulse requires some time to recover and fall again. It will therefore be seen that by the use of the spring the tension on the yarn is kept much more uniform. In addition to its quick action 40 the spring is much lighter, and therefore assists in reducing the total weight of the carrier, which is a very desirable feature where high speed is required.

To withdraw the yarn from the spool, the 45 bottom weight is first raised against the tension of the spring 22, and the plug 21 comes in contact with the end of the guide-pin 7 and through it the latch 8 is raised to the upper lip of the notch 10 in the spindle 9, which allows said latch to just clear the upper edge of 50 the tooth with which it was engaged on the spool 23, releasing said spool, which is thereby left free to turn. The instant the spool starts to turn the tension on the yarn is released, and through the medium of the spring 55 22 the bottom weight is quickly forced down, allowing the latch to fall immediately, catching the next tooth, and allowing but one to pass at a time. The overrunning of the yarn 60 is thus obviated, preventing more yarn than is required from being drawn off, which often happens in the old-style carrier by a sudden impulse given by a jerk on the yarn, in which case there would be no tension on the yarn, 65 and the braid is spoiled. To take the spool

from the spindle, the latch does not have to be removed from the carrier. The forked end is pressed to one side out of the notch 10, and the latch is simply raised and swung around clear of the spindle on its pin in the 70 tubular standard.

Having thus described our invention, what we claim as new, and desire to secure by Letters Patent, is—

1. In a spool-carrier, a spindle on which is 75 mounted a spool or bobbin, a latch for engaging said spool, a tubular standard, and means including a spring in said standard to act on the latch and immediately stop the delivery of yarn when the tension on the same is released.

2. In a spool-carrier, the combination of a spindle on which a spool is mounted, a spring-actuated latch for engaging both the spool and the spindle, a tubular standard, and means 85 whereby the bottom weight raises said latch and allows the spool to turn when yarn is to be drawn from said spool.

3. In a spool-carrier, a spindle on which a spool is mounted, said spindle being provided 90 with a retaining-notch in its upper end, a latch for engaging said spool to prevent it from turning, said latch also being arranged to engage the notch in said spindle, a bottom weight, a standard on which said bottom weight slides, 95 and means whereby said bottom weight will raise the latch and allow the spool to turn when yarn is to be drawn from the spool.

4. In a spool-carrier, a spindle on which a spool is mounted, said spindle being provided 100 with a retaining-notch in its upper end, a latch for engaging said spool to hold it from turning, said latch also being arranged to engage the notch in said spindle, a guide-pin depending from said latch, a bottom weight, a standard 105 on which said bottom weight is held to slide vertically, a tension-spring acting on said bottom weight and means whereby said bottom weight may engage said pin to raise the latch and allow the spool to turn when yarn 110 is to be drawn from said spool.

5. In a spool-carrier, a spindle on which a spool is mounted said spindle being provided 115 with a retaining-notch in its upper end, a latch for engaging said spool, said latch also being arranged to engage the notch in said spindle, a spring on said latch to prevent it from being disengaged from said spindle while the machine is running, a bottom weight, a standard 120 on which said bottom weight slides, a tension-spring acting on said bottom weight, and means whereby said bottom weight will raise the latch to allow the spool to turn when yarn 125 is to be drawn from said spool.

6. In a spool-carrier, a spindle on which a spool is mounted said spindle being provided 130 with a retaining-notch in the upper end thereof, a latch arranged to engage said spindle, a spring on said latch to prevent it from being disengaged from said spindle when the ma-

chine is running, said latch being also arranged to engage said spool and prevent an excessive rotary movement of the same, and means for raising said latch to allow the spool 5 to turn when yarn is to be drawn from the spool.

7. In a spool-carrier, the combination of a spindle on which a spool is mounted, said spindle being provided with a retaining-notch in 10 the upper end thereof, a latch arranged to engage said spool and also to engage the said notch in the spindle, a spring on said latch to prevent it from being disengaged from said spindle when the machine is running, a tubular 15 standard, a guide-pin depending from said latch into said tubular standard and means whereby the bottom weight engages said pin to raise the latch and allow the spool to turn when yarn is to be drawn from said spool.

20 8. In a spool-carrier, the combination of a spindle on which a spool is mounted, a latch for engaging said spool, a bottom weight, a tubular standard having a flattened portion with projecting edges which edges engage said bottom weight to hold it onto said standard as it 25 slides vertically, a guide-pin depending from said latch into said tubular standard, a tension-spring within said standard acting on said bottom weight, and means whereby the bottom weight engages said pin to raise the latch and allow the spool to turn when yarn is to be drawn from the spool.

9. In a spool-carrier, the combination of a spindle on which is mounted a ratchet-head 30 spool, a latch for engaging the teeth of said spool a tubular standard having a slotted back, a guide-pin depending from said said latch into said tubular standard, a bottom weight

through which the yarn is threaded arranged to slide vertically on said standard, an extension on said bottom weight projecting through the slotted back into said tubular standard, a tension-spring within said tubular standard arranged to act on said bottom-weight extension, and means whereby the bottom weight 40 also engages said pin to raise the latch and allow the spool to turn when yarn is to be drawn from the spool.

10. In a spool-carrier, the combination of a spindle on which is mounted a ratchet-head 45 spool, said spindle being provided with a retaining-notch in its upper end, a latch for engaging the teeth of the spool and also being arranged to engage the notch in said spindle, a spring acting on said latch to keep it in engagement with the notch in said spindle, a tubular standard having a slotted back, a guide-pin depending from said latch into said tubular standard, a bottom weight through which the yarn is threaded arranged to slide vertically on said standard, an extension on said bottom weight projecting through the slotted back into said tubular standard, a tension-spring within said tubular standard arranged 55 to act on said bottom weight and means whereby the bottom weight also engages said pin to raise the latch and allow the spool to turn when yarn is to be drawn from said spool.

In testimony whereof we have hereunto set our hands this 22d day of June, A. D. 1904. 60

JOHN McCHEY.
